CONDENSER TAB ATTACHING APPARATUS

Felix Weiss, Plainfield, N. J., assignor to Cornell-Dubilier Electric Corporation, a corporation of Delaware

Application April 12, 1940, Serial No. 329,313

12 Claims. (Cl. 218—1)

This invention relates to apparatus for attaching terminal tabs to the conducting strips of electrical condensers, and has for its object to provide a mechanism which efficiently attaches the tab with a good electrical contact.

It is frequently the practice to attach electrical conducting tabs, for connection with the condenser terminals, to one or more of the conducting strips of electrical condensers which are of the type made by rolling up conducting strips between insulating strips. The conducting strips and the tabs are ordinarily a metal foil.

By the use of this invention the tab is quickly and permanently staked to the condenser sheet.

The invention will be understood from the following detailed description when taken in connection with the accompanying drawings, of which,

Fig. 1 shows a side view, partially in section, of the tab-attaching device;

Fig. 2 is an enlarged full sectional view taken from the same side of the device as Fig. 1;

Fig. 3 is a sectional view taken along line 3—3 of Fig. 1, showing a punch and die arrangement used in this device, the mechanism being shown in the unoperated condition ready to attach a tab to a condenser foil;

Fig. 4 shows the same view as Fig. 3 but with the punch mechanism partially operated toward closed position;

Fig. 5 shows the same view as Figs. 3 and 4 but with the punch mechanism moved to the completely closed position;

Fig. 6 shows a detail of a part of the device which moves a tab over the condenser sheet;

Fig. 7 shows a tab staked to a condenser foil in accordance with the operation shown in Figs. 3, 4 and 5;

Fig. 8 shows a side view of a condenser winding machine having the tab-staking device incorporated therein; and

Fig. 9 shows a top view of the winding machine and staking device shown in Fig. 8.

The device of Figs. 1 to 6 comprises a fixed lower jaw 10 suitably attached to a support 14 which should be firmly secured to a base (not shown) and a movable jaw 12 located above the fixed jaw 10. Jaw 12 is movable in a vertical direction on a depending slide 13 having its central portion slotted from jaw 12 down to near the bottom of the slide, the two arms 13a and 13b of the slide being slidable through guides running vertically through the support 14 of jaw 10. The lower end of slide 13 has attached to it a base 15 which is operated on by a link toggle mecha-

nism which when operated serves to pull jaw 12 downward against the compression force of spring 16. The link toggle mechanism (shown in Figs. 1 and 8) comprises a pin 17 fastened to the fixed jaw 10, this pin carrying a link 18 which is linked at a pin 19 to the arm 20 of a bell-crank which is pivoted at 21 to the base 15 of the movable jaw. Linked to the outer end of the other bellcrank arm 22 is a rod 23 which may be attached to a foot pedal (not shown) so that when the pedal is depressed the rod 23 is pulled down, thereby rotating the bellcrank to pull down the movable jaw 12 with great force.

There are fitted into the lower surface of movable jaw 12, three punches 24, 25 and 26. Each punch has an upper threaded end 27 (see Fig. 2) adapted to thread into a threaded hole 28 which extends vertically through the upper jaw 12. The lower end of each punch is pointed in the form of a nail point 29 in the general shape of a pyramid having several flat sides and corners as shown; and above the point there is provided a collar 30 having a shoulder 31. To hold the punch at the right elevation with respect to the jaw there is provided a locking screw 32 in the hole 28 above the punch shank 27 which is screwed down tightly against the top of screw 27, there being provided set screws 33 and 34 for holding the screws 27 and 32 in place.

Protruding up from the fixed jaw 10 are three dies 35, 36 and 37 corresponding to the three punches 24, 25 and 26. These dies similarly have threaded ends 38 which thread into holes in the jaw, the dies having collars with shoulders 39 that bear on the flat surface of the jaw. Each die is provided with a cylindrical hole 40 of the proper diameter to receive the lower end of the punch when the upper jaw is depressed, and a flat surface or shoulder 41. In the depressing operation, the punch can enter the hole 40 of the die until the shoulders 39 and 41 engage.

A plate 42 is held horizontally below jaw 12 by studs 43 and 44 the heads of which rest on shoulders placed in holes through the jaw and on the lower ends of which the plate is fastened by such means as screws. Compression springs 45 are placed around the studs to hold plate 42 normally in its lowermost position. Plate 42 is provided with three holes 47 properly placed and of the proper diameter to allow the collars 30 of the three punches to pass through with sufficient clearance not to bind. The punch points are preferably located, in their normal unoperated positions, to lie within the respective hole 47 just above the bottom surface of plate 42, as shown

in Fig. 3; although it could operate even if the point should lie somewhat below the bottom surface of plate 42.

A similar plate 50 is supported by studs 51 and 52 the heads of which rest against shoulders in holes through jaw 10, this plate being held in its uppermost position by springs 53 placed around the supporting studs. Plate 50 is provided with three holes 55 of the proper position and diameter to allow the upper end of dies 35, 36 and 37 to pass easily therethrough; and in the normal unoperated position of the device, these dies are situated within their respective holes as shown in Fig. 3. When jaw 12 is pulled all the way down by operation of lever 23, the punches, plates and dies take the position shown in Fig. 5, the punch being within the die, the plate 42 being forced against the under surface of jaw 12 against the compression of springs 45, and plate 50 being pushed further down over the dies against the compression of springs 53. To produce this action, springs 45 should be somewhat weaker than springs 53 so that plate 42 is pushed back toward its jaw 12 before plate 50 is pushed toward its jaw 10.

There are fixed to jaws 10 and 12, respectively, knives 90 and 91 having knife edges 92 and 93, which cut off the foil tab strip 100 which is between them when the upper jaw 12 is depressed.

For the purpose of supplying tab material to the punch and die member there is provided a roll 58 containing the strip 100 of tab material, which is preferably a heavy metal foil, mounted on a spindle 59. To feed this foil strip to the punch there is provided a frame containing two side plates 60 and 61, the forward ends of which are bolted to the upright member 14 of the fixed jaw. The other ends of these side plates are supported by legs 62 which may be fastened to a suitable base. Each of the plates is provided with a vertical slot 64 above the legs, to receive the spindle 59, and there is provided an arcuate flooring strip 65 fastened between the rear bottom parts of the side pieces, on which the rim of the foil roll rests. The width of this strip is such as to permit a proper spacing between the side plates to allow the foil roll freely to rotate between them.

There are provided a pair of rigid rounded rods 56 and 57 (Fig. 6) fastened at their front ends to the lower jaw support 14 by brackets 66 and fastened at their rear ends to flooring strip 65. The rods are provided respectively with horizontal slots 48 and 49, into which the respective edges of the foil strip 100 from the roll are inserted, so that the strip can be carried forward along the slots. To prevent back lash of the foil there is provided a pawl 67 pivoted on a pin 69 passing between the side plates. A spring 70 bearing on the pawl causes the pawl to rotate down against the flat top 68 of the lower jaw support 14, so that the foil strip which has passed from slots 48 and 49 through the opening in slide 13, passes over jaw support 14 and under the pawl, which thus bears down on the strip.

For the purpose of feeding forward lengths of the foil tab 100 there is provided a manual feeding device 71 (Fig. 6) in the form of a frame 72 having a flat platform 73, even with slots 48 and 49, over which the foil strip can slide. There is formed in each side of the frame a rounded groove which is adapted to fit over and slide along the rounded rods 56 and 57. The upper

portion of the frame is provided with a pin 74 having pivoted on it a member 75 which has attached to it one end of a helical tension spring 76 passing around pin 74, the other end being placed against the side of the frame at 77 so that member 75 tends to rotate counterclockwise (with reference to Fig. 2). At the top of the left end of member 75, referring to Fig. 2, there is a curved finger piece 78, and at the opposite end there is a depending lip 79 which is normally kept out of engagement with the foil strip 100 by action of the spring 76. At the bottom 73 of the frame piece there is a depending pin 84 to which is attached one end of a long coiled spring 85. This spring is carried over a pulley 86 which is freely rotatable on a pin 87 fastened between the side plates 60 and 61, and has its opposite end fastened to a pin 88 which is also fixed between the side plates. Spring 85 tends to hold member 71 against a stop in the form of a clip block 117 fastened over its sides 60 and 61. At the bottom of the block is a short curved member 118, having attached to its under surface a soft piece 119 such as felt which is in contact with the tab strip 100 passing under it.

The parts are so arranged that when the operator pulls member 71 to the right (with reference to Fig. 2) by placing his finger in the curved finger grip, the lip 79 is depressed against the force of spring 76 into contact with the foil strip on the track, thus pulling the foil forward until the frame of member 71 strikes a stop 88 in the form of a block which may be placed over the walls 60 and 61 at any desired position, and fastened by a set screw, the position of this stop determining the length of foil strip which is fed along the track and out through the space between legs 13 to a position between plates 42 and 50, by each operation of member 71.

This tab staking device is especially effective when used in cooperation with a roll winding machine such as is commonly used for winding foil and insulating strips on a mandrel to form the condensers. Such an arrangement is shown in Figs. 8 and 9, the member 14 of the jaw 10 being attached to the frame 94 of the winding machine, so that the space between the plates 42 and 50 lies in the path of the condenser foil travelling to the mandrel. The winding machine is of a general form, well-known in the art, having a number of spindles 95 fastened to the frame, on which are placed the several conducting and insulating strip rolls, the strips of which are suitably led between rollers 110 and 111 to a winding mandrel 96 which may be power-driven by a pulley 97 and belt 98 to roll up the strips into the condenser roll. The foil strip 99 which is to be tabbed, is shown carried over a pin 112, then under a pin 113, then guided between the plates 42 and 50 on its way to the mandrel.

When it is desired to stake a tab the rotation of the mandrel is stopped, and the operator by operation of finger member 78 feeds a length of tab which thus passes from the track, over knife blade 90 and then over foil 99 and under plate 42, so that the length of the tab strip is perpendicular to the length of the condenser strip, in the arrangement shown. This feeding occurs because the pressure on member 78 rotates lip 79 into frictional engagement with the tab strip, and also slides the entire frame 72 along the rods 56 and 57 against the tension of spring 85. The finger piece can then be released, allowing the member 71 to be pulled back by spring 85.

out of engagement with the tab material and against the stop 117. The stop 89 should previously be set relative to the width of the foil strip 99 so that when the operator pulls forward the finger piece 18 there will be fed over the foil strip a length of tab just sufficient to cross the foil.

The staking operation is then performed by a quick pressure on the foot lever 23 which by pulling down jaw 12 rapidly performs the following sequence: Plates 42 and 50 are brought together, holding the foil strip and tab firmly in position between them. Then springs 45 compress so that the punch points come down through the respective holes in plate 42 and pierce the tab and foil, tearing the material in the manner illustrated in Fig. 4 so that pointed ends 101 and 102 are formed respectively of the foil and the tab material.

The punch continues to pass through the aligned holes in plates 42 and 50, and then the springs 53 of plate 50 compress so that plate 50 then moves down over the dies. Finally, the shoulders 31 and 41 of the punch and die crimp between them the turned ends 101 and 102 of the foil and tab into the position shown in Fig. 5. At the same time the knife blades 90 and 91 sever the tab, leaving a definite length protruding from the side of the condenser foil, as shown in Fig. 7. The end of the condenser foil may then be severed at 103 in any desired manner. Then the foot lever is released, allowing the jaw to retract to the normal position by action of the springs, thus leaving a well staked permanent tab as shown in Fig. 7.

The foil strip forming the other conducting strip of the condenser may for example have had a terminal tab already staked to it by a previous operation without the winding machine; and this other strip if short enough may be held in the operator's hand as it is fed to the mandrel; or alternatively, this other strip might have an unstaked tab attached to it by rolling the end of the foil strip over the tab in a well known manner.

Although the tab-staking device is shown in cooperation with the winding machine its use is not limited to this machine, for terminal tabs might be staked to condenser foils whether the condensers are being wound on the machine or not.

I claim:

1. A machine for winding roll condensers comprising a winding mandrel and sources of conducting and insulating strips which are to be wound on the mandrel to form the condensers, the conducting strips being separated from each other in their path of travel to the mandrel, a plate having a hole over which a separated conducting strip passes, a punch located on the side of the last mentioned conducting strip opposite from said plate, said punch having a shoulder and terminating in a point which is positioned to pass through said hole, a cooperating die having a hole adapted to receive the punch point and a shoulder around the die hole adapted to abut against the shoulder of the punch, a source of terminal tab strip located adjacent the plate, a strip feeder operable to feed a length of said tab strip between said punch and plate and across the surface of the last-mentioned conducting strip, where it may be attached to the last-mentioned conducting strip by operation of the punch.

2. In a machine for winding roll condensers

comprising a winding mandrel and sources of conducting and insulating strips which are to be wound on the mandrel to form the condensers, the conducting strips being separated from each other in their path of travel to the mandrel: a pair of plates facing each other between which one of said separated conducting strips passes, each of said plates being provided with holes, there being punch points with shoulders back 5 of the points adapted to protrude through the holes in one of said plates and through the last-mentioned conducting strip, and there being corresponding dies adapted to protrude through the holes of the other plate to meet the punches, said 10 plates being resiliently compressible toward the punches and dies respectively when the punches are operated toward the dies, a source of terminal tab strip located beside said pair of plates, a strip feeder operable to feed lengths of said 15 tab strip between said plates and across the surface of the last-mentioned conducting strip, and a knife correlated with the punches for cutting off said tab from its supply at a position outside the edge of said conducting strip when 20 the punches are operated into the dies.

3. A machine for winding roll condensers comprising a winding mandrel and sources of conducting and insulating strips which are to be wound on the mandrel to form the condensers, 25 the conducting strips being separated from each other in their path of travel to the mandrel, a punch having a shoulder and terminating in a point and a cooperating die having a hole adapted to receive the punch point and a shoulder 30 on its end adapted to abut against the shoulder of the punch, a plate having a hole through which the die and its shoulder may protrude, resiliently held in front of the die and compressible toward the die after the punch enters said hole, 35 said punch and plate being located on opposite sides of at least one of said separated conducting strips, a source of terminal tab strip located beside the conducting strip which passes between the punch and plate, a strip feeder operable to 40 feed a length of said tab strip between said punch and plate and across the surface of the last-mentioned conducting strip, whereby a condenser may be rolled on the mandrel, a tab attached before completion of the roll, and the 45 winding of the roll then completed on the mandrel.

4. Tab attaching mechanism comprising a pointed punch having a shoulder located back of the point, a cooperating die having a hole dimensioned to receive the punch point and having around the hole a shoulder adapted to abut against the shoulder of the punch, said punch and die being held by respective cooperating jaws, a plate provided with a hole through which the 55 punch and its shoulder may protrude, said plate being mounted on studs each of which has a shoulder adapted to rest against a shoulder of the punch holding jaw, spring means for resiliently holding the stud shoulders against the jaw shoulders to hold said plate substantially at or in front of the punch point, a second plate having a hole through which the die may protrude, said second plate being mounted on studs each of which has a shoulder adapted to rest against a shoulder 60 of the die holding jaw, and spring means for resiliently holding the shoulders of the last mentioned studs against the shoulders of the die holding jaw to hold said second plate in front of the die, and somewhat apart from, and facing, 65 the first mentioned plate.

5. Tab attaching mechanism comprising a pointed punch having a shoulder located back of the point, a cooperating die having a hole dimensioned to receive the punch point and having around the hole a shoulder adapted to abut against the shoulder of the punch, said punch and die being held by respective cooperating jaws, a compressible plate mounted on plural spring supported studs to the die holding jaw and resiliently held in front of the shoulder of the die, and a second compressible plate mounted on plural spring supported studs to the punch holding jaw and resiliently held in front of the punch point and facing the first mentioned plate, said first mentioned plate having an opening through which the die and its shoulder may protrude and the second plate having an opening through which the punch and its shoulder may protrude, whereby when the punch and die are moved together, strips of material between the plates are gripped by the plates, then buried by the punch and then the burrs are flattened between the shoulders.

6. Condenser tab attaching mechanism comprising pointed punches having shoulders located back of the points, cooperating dies having holes dimensioned to receive the corresponding punch points and shoulders around the die holes adapted to abut against the shoulders of the punches, said punches and dies being held by respective cooperating jaws, a gripping plate provided with holes through which the punches and their shoulders may protrude, said plate being mounted on spring supported studs affixed to the punch holding jaw and resiliently held at or in front of the punch points, a second gripping plate having holes through which the dies and their shoulders may protrude, said second plate being mounted on spring supported studs affixed to the die holding jaw and resiliently held in front of the dies and somewhat apart from and facing the first mentioned gripping plate.

7. In a machine for winding roll condensers comprising a winding mandrel and source of conducting and insulating strips which are to be wound on the mandrel to form the condensers, the conducting strips being separated from each other in their path of travel to the mandrel: a pair of plates facing each other between which one of said separated conducting strips passes, each of said plates being provided with holes, there being punch points with shoulders back of the points adapted to protrude through the holes in one of said plates and through the last-mentioned conducting strip, and there being corresponding dies adapted to protrude through the holes of the other plate to meet the punches, said plates being resiliently compressible toward the punches and dies respectively and compressible toward each other so as to grip said conducting strip and the terminal tab fed across it from a source located beside said pair of plates so as to position same to be punched by the operation of the punches and corresponding dies, and a knife correlated with the punches for cutting off definite lengths of tab from its supply at a position outside of said conducting strip when the punches are operated.

8. In a machine for winding roll condensers comprising a winding mandrel and source of conducting and insulating strips which are to be wound on the mandrel to form the condensers, the conducting strips being separated from each other in their path of travel to mandrel: a pair of plates facing each other between which one of

said separated conducting strips passes, each of said plates being provided with holes, there being punch points with shoulders back of the points adapted to protrude through the holes in one of said plates and through the last-mentioned conducting strip, and there being corresponding dies adapted to protrude through the holes of the other plate to meet the punches, a strip feeder located beside said pair of plates operable to feed lengths of tab strip between said plates and across the surface of the last-mentioned conducting strip, said plates being mounted on spring supported studs and compressible toward each other and toward their respective punches and dies when the punches are operated toward the dies while the winding mandrel is stopped so as to grip momentarily said conducting strip and said tab fed from the aforesaid source, and a knife actuated by movement of the punch to cut off definite lengths of terminal tab from its supply at a position outside of said conducting strip.

9. In a machine for winding roll condensers comprising a winding mandrel and source of conducting and insulating strips which are to be wound on the mandrel to form the condensers, the conducting strips being separated from each other in their path of travel to the mandrel: a plate having a hole under which a separated conducting strip passes, a punch with a shoulder and terminating in a point which is positioned to pass through the hole of said plate, a second plate having a hole positioned opposite the hole of said first-mentioned plate and over which said separated conducting strip passes, a die positioned in the hole of said second plate to receive the punch point and having a shoulder to abut against the shoulder of the punch, said punch and die being held by cooperating jaws, spring means for resiliently holding the aforementioned plates in front of the punch point and cooperating die and sufficiently separated to permit the conducting strip to pass freely therebetween, a strip feeder adjacent to the plates operable to feed a length of tab strip from a supply source between the plates and across the surface of the conducting strip, means for actuating the jaws so that the tab and conducting strip are first gripped by said plates, so as to position them to be pierced by the punch at the same time that the definite tab length is cut after which the pierced ends of the tab and conducting strip are turned back and flattened between the shoulders of the punch and die.

10. In a machine for applying tabs to condenser foils the combination with a pair of plates, a mechanism for feeding foil and tab strips between said plates in position to be fastened together, operating means for moving said plates to press said foil and tab strips together in said fastening position, subsequently acting punch means actuated by a continued movement of said operating means to pierce through the tab strips within the area being gripped by said plates and to bend apart the ends formed by the piercing, and subsequently operated die means actuated by further movement of said operating means and cooperating with said punch means to crimp over said ends so as to secure the tab to the foil strip within the area being gripped by said plates.

11. The combination as set forth in claim 10 in which operating means for one of the clamping plates carries the punching mechanism and comprises relatively weak spring supporting means for the plate, and operating means for the other plate carries the die means and has a supporting means of sufficiently greater resistance to support

the strips resiliently during the piercing thereof in advance of the crimping by the die means.

12. In a machine for applying tabs to condenser foils the combination with a pair of plates, a mechanism for feeding foil and tab strips between said plates in position to be fastened together, members resiliently supporting said plates and relatively movable to bring said plates together floatingly to grip said foil and said tab strips in said fastening position between said plates, sub- 10 subsequently acting punch means actuated by a con-

tinued movement of said operating means to pierce through the tab strips within the area being gripped by said plates and to bend apart the ends formed by the piercing, and subsequently operated die means actuated by further movement of said supporting members and cooperating with said punch means to crimp over said ends so as to secure the tab to the foil strip within the area being gripped by said plates.

FELIX WEISS.
